FLEXIBLE SHAFTING

George G. Eisenbeis, Conklin, N. Y., assignor to
Stow Manufacturing Co., New York, N. Y., a
corporation of New York

Application March 3, 1944, Serial No. 524,958

3 Claims. (Cl. 308—36.2)

This invention relates to improvements in flexible shafting, and more particularly to a combined deck-plate or bulkhead fitting and flexible shafting terminal assembly for carrying a flexible shaft drive-fitting through a deck or bulkhead, for example, and to provide a deck station at which power may be applied to the shaft.

As is well known, flexible shafting is widely used on shipboard for the transmission of power and for the remote control of mechanisms operating from a distance. One of the difficulties of the prior constructions has been the failure to provide a simple and satisfactory terminal assembly which can be installed at any given angle with the deck of a ship or other structure through which the terminal passes. Where it is required to have the shaft terminal inclined to the deck or bulkhead, irregularly shaped or elliptical openings requiring special technique or involving extra man hours were usually employed. One object of the invention is to provide an angularly adjustable deck-plate or bulkhead fitting and terminal assembly which can be mounted at various inclinations relative to a deck or bulkhead provided with a circular opening for the terminal, and thereupon secured to the deck plate or bulkhead as by welding.

Another difficulty encountered in the prior constructions was that the deck mounting and flexible shaft terminal were made of separate parts. The present invention contemplates a combination deck-plate or bulkhead fitting and flexible shaft terminal incorporated into a unitary self-contained structural assembly of simple design capable of economical installation.

It is a further object of the invention to provide a flexible shaft terminal capable of locating the shaft during assembly, and thereupon of permitting free rotation of the shaft while at the same time definitely and positively restraining the shaft from axial displacement. According to a further object the terminal assembly as aforesaid incorporates a novel arrangement of shaft packing which functions to prevent leakage of water through the terminal.

Other objects will be in part obvious and in part hereinafter pointed out in connection with the following analysis of the invention wherein is illustrated one embodiment of the invention in detail.

In the drawing:

The figure is a longitudinal part section of the deck or bulkhead terminal assembly according to the invention.

Referring to the drawing, reference character

1 indicates a conventional flexible shaft core comprising, for example, a plurality of superimposed layers of wire helically wound on a central wire, and being enclosed within the usual flexible metal casing 2, in which the core is free to rotate. Shaft core 1 terminates in a rod-type drive fitting 3 which, as shown, has its end reduced as at 4 to receive a hand wheel (not shown) or equivalent driving means. Intermediate its ends the rod fitting is provided with a shoulder 5, preferably formed integrally therewith, for the purpose to be described.

According to the invention, the core 1 and fitting 3 extends through a tubular sleeve 6 of suitable metal such as steel, which constitutes a deck-plate or bulkhead fitting sleeve, to one end of which the casing 2 is interiorly secured as by soldering. Sleeve 6 is adapted to extend through a deck plate or bulkhead 10 and, with the flexible shaft core and its drive fitting 3 extending through the sleeve, the latter thus provides a means for carrying the shaft through the bulkhead or deck plate, so that the drive fitting 3 is readily accessible from the relatively outer or weather side thereof, thereby to provide a deck station from which the shaft may be operated.

To permit connection of the sleeve to the plate or wall 10 at any required angle without the necessity of a specially shaped opening through the latter, the sleeve intermediate its ends is provided with a part-spherical enlargement 7, whereby in passing through a circularly formed opening 11 in the plate or wall, the sleeve may be adjusted to a desired angular relationship therewith in the manner of a ball joint. Hence, the plate and sleeve may have right-angular relationship as shown in the drawing, or the sleeve may be inclined to the plate at any angle, within the obvious limitation of a sleeve to plate mounting, required for a particular installation as typified by the dotted line relationship of plate to sleeve. Upon the sleeve being initially adjusted, it is fixedly secured to the plate or wall as by welding.

The invention also provides means for packing the shaft fitting 3 within the sleeve so as to preclude leakage through the terminal, provision being also made to restrain the fitting and hence the core 1 against axial displacement relative to the sleeve. To these ends the relatively outer or weather end of the sleeve is exteriorly threaded to receive a securing nut 12 formed with an inwardly directed end flange 13, and a lock nut 14 for locking the securing nut in position on the sleeve. The end flange 13 engages against the

outer end face of a tubular follower 15 which extends into the sleeve, being disposed about the rod fitting 3, the follower having inner and outer diameters permitting axial movement thereof relative to both the fitting and the enclosing sleeve.

Adjacent its part-spherical enlargement 7, the sleeve bore is provided with a vertical shoulder 16 forming an abutment for a cylindrically flanged thrust washer 18 arranged to provide an open-sided ring groove for the rod shoulder 5. This groove is in effect closed at its open side by a gland ring 19 surrounding the fitting, one end face of which bears against the flange of the thrust washer 18. The width and depth of the groove formed by the arrangement of thrust washer and gland ring as aforesaid is such as to provide turning clearance for the rod shoulder, it being understood that the thrust washer 18 serves to preclude axial movement of the fitting to the left in the drawing. The engaging surfaces of the rod collar, washer and ring are supplied with lubricant through a grease fitting 20 substantially as shown.

To prevent leakage through the terminal, packing in the nature of a plurality of packing rings 21, which advantageously can be formed from packing material such as braided asbestos, are placed around the rod fitting in the space between the follower 15 and gland ring 19. Preferably, the adjacent end faces of the follower and gland ring are oppositely beveled as shown, so that the spacing between end faces is somewhat less at their outer peripheries than at their inner peripheries. Hence, as nut 12 is turned to force the follower into the sleeve, the beveled faces of the follower and gland ring not only compress the packing axially but also constrict the packing radially inwardly into tight engagement with the rod fitting 3, thereby to provide a water-tight joint between sleeve and fitting, while at the same time permitting rotation of the fitting and flexible shaft core coupled thereto. Tightening of nut 12 also transmits pressure in axial direction to the gland ring 19 to force the same into tight engagement with the thrust washer 18, thus to securely hold the parts in assembled relation, and also to secure the rod fitting 3 against axial displacement to the right, as shown in the drawing.

A combined deck-plate fitting and flexible shafting terminal as described and its shafting may be assembled complete at the factory and shipped ready to install. To assemble, the shaft casing 2 is first soldered to the inner end of the sleeve 6 as shown. The driven end of the shaft core is then threaded through the thrust washer 18, and the core fed into the sleeve 6, the washer locating itself against the vertical sleeve shoulder 16. The operation of feeding the shaft into the sleeve is continued until the rod shoulder 5 engages the washer, thereby finally locating the shaft axially relative to the sleeve. The gland ring 19, the packing rings 21, and the follower 15 are in that order now slipped over the free end of the fitting 3 and are slid home into the space between the sleeve and fitting. Finally, the locking and securing nuts 12, 14, are threaded on to the sleeve and, upon tightening thereof, the parts are secured in finally assembled position.

To install, the combined fitting and terminal is passed through a preformed circular opening 11 provided in the deck plate or bulkhead at the desired location, until the enlarged, part-spherical portion 7 of the sleeve is centered in the open-

ing. Upon adjusting the sleeve to its required angular position with respect to the deck plate or bulkhead, the sleeve is secured as by welding, and the installation is now complete.

The fitting and terminal assembly as described above is of simple design and construction and may be readily installed in any desired location where a deck station for applying power to the shafting may be required. In addition to providing a practical and economical means of securing the shafting terminal in desired angular position with respect to a bulkhead, deck plate or equivalent wall, the present fitting and terminal assembly combines into a single structure the shaft terminal and a fitting providing for the mounting of the terminal relative to deck-plate or bulkhead, which previously were made separately. It will be noted also that the novel deck-plate fitting and terminal assembly according to the invention incorporates simple and practical means for positively locating the shaft axially relative to the terminal as well as for restraining the shaft against axial displacement when finally located. Moreover, the fitting and terminal assembly of the invention incorporates effective yet simple means of packing the shaft, thereby to prevent leakage of water through the terminal, an important consideration when the deck station is open to the weather.

As many changes could be made in carrying out the above construction without departing from the scope of the invention, it is intended that all matter contained in the above description or shown in the accompanying drawing shall be interpreted as illustrative and not in a limiting sense.

I claim:

1. A combined deck-plate fitting and terminal for flexible shafting of the type having a rotary power transmitting core enclosed within a casing comprising a tubular sleeve adapted to extend through a circular opening formed in a deck-plate and being provided intermediate its ends with an enlarged diameter part-spherical portion adapted to be fitted in said opening and which provides for the mounting of the sleeve at any one of various inclinations relative to deck-plate as required for a particular installation, the shafting casing being affixed to one end of the sleeve, the shafting core extending into said sleeve and terminating in a drive fitting therefor, one end of the drive fitting projecting through the other end of the sleeve and being adapted to receive core driving means, and means contained in said other end portion of the sleeve for securing the drive fitting axially relative to said sleeve and for providing a water-tight joint between the sleeve and drive fitting.

2. A combined deck-plate fitting and terminal for flexible shafting of the type having a rotary power transmitting core enclosed within a casing comprising a tubular sleeve adapted to extend through a circular opening formed in a deck-plate and being provided intermediate its ends with an enlarged diameter part-spherical portion adapted to be fitted in said opening and which provides for the mounting of the sleeve at any one of various inclinations relative to deck-plate as required for a particular installation, the shafting casing being affixed to one end of the sleeve, the shafting core extending into said sleeve and terminating in a drive fitting therefor provided with an external shoulder, one end of the drive fitting projecting through the other end of the sleeve and being adapted to re-

ceive core driving means, and means contained in said other end portion of the sleeve and cooperating with the fitting shoulder for securing the drive fitting axially relative to said sleeve and for providing a water-tight joint between sleeve and drive-fitting.

3. A combined deck-plate fitting and terminal for flexible shafting of the type having a rotary power transmitting core enclosed within a casting comprising a tubular sleeve adapted to extend through a circular opening formed in a deck-plate and being provided intermediate its ends with an enlarged diameter part-spherical portion adapted to be fitted in said opening and which provides for the mounting of the sleeve at any one of various inclinations relative to

deck-plate as required for a particular installation, the shafting casing being affixed to one end of the sleeve, the shafting core extending into said sleeve and terminating in a drive fitting therefor provided with an external shoulder, one end of the drive fitting projecting through the other end of the sleeve and being adapted to receive core driving means, the bore of the sleeve in its said other end portion being formed with an internal abutment shoulder, and means contained in said bore portion and cooperating with said fitting collar and abutment shoulder for securing the drive fitting axially relative to said sleeve and for providing a water-tight joint between sleeve and drive fitting.

GEORGE G. EISENBEIS.
